United States Patent

Des. 236,545
Patented Aug. 26, 1975

236,545

VIDEOPLAYER

James H. Sias, Rochester, N.Y., assignor to Eastman
Kodak Company, Rochester, N.Y.

Filed Jan. 12, 1973, Ser. No. 323,018

Term of patent 14 years

Int. Cl. D16—02

U.S. Cl. D61—1 K

FIG. 1

FIG. 2

FIG. 3

FIG. 4

FIG. 5

FIG. 6

FIG. 7

FIG. 1 is a top plan view of a videoplayer showing my new design;

FIG. 2 is a bottom plan view thereof;
FIG. 3 is a rear side elevational view thereof;
FIG. 4 is a front side elevational view thereof;
FIG. 5 is a right side elevational view thereof;
FIG. 6 is a left side elevational view thereof; and
FIG. 7 is a top, front perspective view thereof.

I claim:

An ornamental design for a videoplayer, as shown.
